(57)

CLAIM

The ornamental design for a sledgehammer, as shown and described.

DESCRIPTION

FIG. 1 is a perspective view of a sledge hammer embodying my new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The broken lines in the drawings depict features of the sledgehammer that form no part of the claim.
